(57) **CLAIM**

The ornamental design for a PDC cutter, as shown and described.

DESCRIPTION

FIG. 1 is a perspective view of a PDC cutter, according to my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is a cross section view, taken along the line 8-8, as seen in FIG. 6.

The broken lines show portions of a PDC Cutter which form no part of the claimed design.

The “dash-dot” broken line seen in FIG. 8 shows the bounds of the claimed design, and forms no part thereof.
